UNITED STATES PATENT OFFICE.

MELVIN E. MERKER, OF NEW YORK, N. Y., ASSIGNOR TO MERKER INTERCHANGEABLE TOOTH CORPORATION, OF NEW YORK, N. Y., A CORPORATION OF NEW YORK.

ARTIFICIAL TOOTH.

1,341,813.

Specification of Letters Patent.

Patented June 1, 1920.

Application filed June 30, 1917, Serial No. 177,939. Renewed August 26, 1919. Serial No. 320,047.

To all whom it may concern:

Be it known that I, MELVIN E. MERKER, citizen of the United States, residing at New York, county and State of New York, have invented certain new and useful Improvements in Artificial Teeth, of which the following is a specification, reference being had therein to the accompanying drawings.

This invention relates to improvements in 10 artificial teeth, and more particularly to the method of fastening the same to their backings.

The invention has for its object to provide a means for preventing the teeth from 15 working loose on their backings and for preventing their securing pins from loosening during the biting action of the tooth.

Another object of the invention is the provision of a locking means which consists 20 of a tooth provided with a rearwardly extending enlargement having flat faces which extend angularly with relation to each other, each of which is pierced with an opening which extends diagonally of the 25 longitudinal axis of the tooth, and a backing plate which is shaped to conform to the angularity of the faces, which plate carries pins for engagement in the openings, which are arranged diagonally with relation to the 30 tooth so that biting action on said tooth will tend to force the tooth more firmly into place.

With these and other objects in view as 35 will become more apparent as the description proceeds, the invention consists in the novel construction, combination and arrangement of parts set forth in the following specification, pointed out in the appended claims and illustrated in the accompanying drawing, in which,—

Figure 1 is a perspective view of a tooth constructed in accordance with this invention,

Fig. 2 is a sectional view through Fig. 1, 45 Fig. 3 is a sectional view through a modified form of tooth,

Fig. 4 is a rear view of Fig. 3, and

Fig. 5 is a view showing the tooth on the backing plate.

Referring to the drawing by characters of reference, the numeral 1 designates a tooth having a body provided on its rear side with an enlargement 2, which is provided on its rear face, with angularly extending faces 3 and 4, having formed there-

in apertures 5 and 6 respectively. These apertures extend diagonally of the longitudinal axis of the tooth and it will thus be seen that biting action on said tooth will force the tooth more firmly against its 60 backing.

The backing plate is designated by the numeral 7, and is provided with a plurality of angularly arranged faces which coincide with the faces on the tooth in connection with 65 which it is to be used. Pins 8 are carried by the faces of the backing plate and extend angularly with relation to the longitudinal axis of the tooth so that the biting action on the tooth will cause the tooth to 70 more firmly engage the backing plate and bind the parts together.

It will be apparent that in use the tooth is secured to the plate by securing the pins in their respective openings and when they 75 are in place it will be seen that the tooth will be held against accidental movement. Should the tooth tend to move away from the plate it will be seen that the pins will firmly bind against the walls of the apertures and lock the plate and tooth together. Due to the angular relation of the pins and openings with the longitudinal axis of the tooth it will be seen that biting action will 80 more firmly force the tooth against the 85 backing, thus locking the parts against disengagement.

While in the foregoing I have shown and described the preferred embodiment of this invention it is to be understood that certain minor changes in the construction combination and arrangement of parts may be resorted to, without departing from the spirit and scope of the invention, as claimed.

What is claimed is:—

1. An artificial tooth comprising, a tooth body, an enlargement on the rear side of said body, a plurality of flat faces on said enlargement arranged angularly with relation to each other, each of said faces having an opening formed therein and each opening being disposed diagonally with relation to the longitudinal axis of the tooth.

2. An artificial tooth having an enlargement on its rear side, said enlargement being provided with a plurality of angularly disposed faces, each of which is formed with an opening arranged diagonally of the longitudinal axis of the tooth, a backing plate and pins carried by said plate for po- 110

sitioning in the openings to hold the tooth in place on said plate.

3. An artificial tooth having a plurality of flat faces on its rear side, each face having an opening extending thereinto, said openings being arranged diagonally with relation to the longitudinal axis of the tooth and parallel to each other, a backing plate

having a plurality of flat faces arranged to engage the faces on the tooth and pins on said plate to enter the openings in the tooth to anchor said tooth in place.

In testimony whereof I affix my signature.

MELVIN E. MERKER.
